HEAVY BINDER EASEL CONSTRUCTION
Robert C. Cline, Saugerties, N.Y., assignor to F. L. Russell Corporation, Mount Marion, N.Y., a corporation of New York

Filed Apr. 23, 1962, Ser. No. 189,343
2 Claims. (Cl. 281—33)

The invention herein disclosed relates to binders having a built-in easel formation which can be raised to support the pages in an inclined position convenient for reading or display.

Objects of the invention are to provide a simple, practical form of easel structure, suitable for heavy binders.

Other special objects of the invention are to provide a heavy duty easel binder made up of few, self-contained, durable parts, easily operable to shift from a closed binder to an open, page supporting inclined easel relation.

Other desirable objects and the novel features through which the purposes of the invention are attained are set forth and will appear in the course of the following specification.

The drawings accompanying and forming part of the specification, illustrate present practical embodiments of the invention. Structure however, may be modified and changed as regards the immediate illustration, all within the true intent and scope of the invention as hereinafter defined and claimed.

FIG. 1 is a front or face view of the binder, closed in book form.

FIGS. 2 and 3 are back and front views of the same respectively, looking in the direction of arrows 2 and 3 in FIG. 1.

FIG. 4 is a plan of the binder in fully opened relation.

FIGS. 5, 6, 7 and 8 are diagrammatic end views on line 5—5 of FIG. 4, illustrating successive positions in setting up the binder into easel formation.

FIG. 9 is a plan view of the opened binder set up as an easel.

FIGS. 10 and 11 are front and back views respectively of the same.

FIG. 12 is a plan view, illustrating another form of the invention designed as a screw post, nail, staple, prong or similar form of binding, and cover at one side being broken away for lack of space.

FIG. 13 is an end view of this binder set up in easel formation.

FIG. 14 is a front end view of this screw post form of binder, closed in book formation.

The body of the binder is shown in the form of a folder, made up in each instance of front and back covers 20 and 21, hingedly connected on parallel lines 22, 23 to a back member 24, so as to close into compact book formation, as in FIGS. 1, 2 and 3, and to open out into flat form, as in FIG. 4.

The easel formation is shown as an easel board overlying the back and connected covers and made up of side panels 25, 26 of approximately the size of front and back covers 20, 21 and hingedly connected along their lower edges at 27, 28 to the lower edges of said covers.

At the center there is provision for mounting of the binding.

The binding for the sheets, leaves or pages may vary to suit different requirements.

In the first example, FIGS. 1 to 9, the binding is shown in the form of a mechanical ring binder 29 and the mounting provided for it is a back panel 30 overlying and of approximately the size of the back member, hingedly connected along its side edges at 31, 32 with the side panels 25, 26, in line with the cover-to-back hinges 22 and 23 so as not to interfere with opening and closing movements of the binder.

2

At the lower edge this binding supporting back panel 30 is hingedly connected with the lower edge of the back 24 at 33 in line with the side panel hinges 27, 28 so that it will raise and lower with lifting and lowering 5 movement of the side panels constituting the easel board.

The easel board, made up in the first instance of the three hingedly connected panels 25, 30 and 26, FIG. 4, may be raised and lowered as a single unit by taking hold of it at the upper corner edges which may be marked 10 with suitable designations such as indicated at 34.

For supporting the board in lifted inclined relation there is provided a sectional supporting panel made up of strips 35, 36 of stiff material, hingedly connected along their lower edges at 37, 38 with the upper edges 15 of the side panels 25, 26 and hingedly connected along their upper edges at 39, 40 with narrow strips 41, 42 which are hingedly connected along their lower edges at 43, 44 with the upper edges of the front and back covers 20, 21.

The strips 35, 36 are of a width to support the easel board at a desired angle of inclination, such as shown in FIG. 8, and the narrower strips 41, 42 are of a width to serve when turned in over the covers to locate and hold the supports 35, 36 in substantially upright position.

FIG. 5 shows diagrammatically the relation of the parts in the open flat condition illustrated in FIG. 4, with the side panels 25, 26 of the easel board and the support strips 35, 36 lying flat over the front and back covers 20, 21 and the support positioning strips 41, 42 lying flat under the supports 35, 36 in line with the front and back covers 20, 21.

FIG. 6 shows how on lifting the easel board panels 25, 26 the supporting strips or panels 35, 36 will hinge 25 the positioning strips 41, 42 upwardly and will, as the lifting progresses, carry the strips 41, 42 upwardly and over a dead center position, such as in FIG. 7, where they will drop down in back of the lower edges of the supports, resting on the covers 20, 21, as in FIG. 8, and thus locking panels 25, 26 in the supporting position.

To lower the easel it is only necessary to lift the easel panels sufficiently to reverse the action, that is to swing the hingedly connected supporting and positioning strips back through the FIG. 7 and FIG. 6 positions, whereupon the easel board with its supports will automatically return to the flat folded state illustrated in FIG. 5.

FIGS. 9, 10 and 11 show the binder in the opened, easel forming condition and also show how the inner ends of the spacing or positioning strips 41, 42 may be connected by hinges 45, 46 with a short strip 47 which is hinged to the back 24 along the line 48 in line with the hinges 43, 44 connecting the positioning strips 41, 42 with the covers 20, 21 so as to fold and unfold along with the other parts.

If desired the upper end of the back piece 30 may 55 be supported in the inclined position by a small block or panel hingedly connected with the upper end of said back piece and hingedly connected with the small strip 47 connecting the positioning strips 41, 42, though this extra support is ordinarily not considered necessary.

The modification illustrated in FIGS. 12, 13 and 14 60 differs from the construction described in that it is made to take a binding on the order of a screw post binder.

For that reason the center section of the easel board, over the back 24, is made up of upstanding flanges 49, 50 hingedly connected at 51, 52 with the inner edges of the side panels 25, 26 of the board and provided with holes 53 spaced to receive the screw posts, nails, staples or other fastenings used for holding the sheets or pages 65 in place.

The structure otherwise may be the same as first disclosed.

In practice this central binder or binding supporting section may be provided by splitting the center section 30, FIG. 4, into separated strips to form the flanges 49, 50 hingedly connected with the side panels and provided with means for securing the bound sheets together and the side panels hingedly connected together in line with the covers of the binder.

The invention provides a strong, durable structure particularly suited for heavy binders, with no loose, sliding parts to get out of order and which may be made up at 10 low cost because constructed mainly of flat panels of cardboard or similar rigid, stiff, inexpensive material.

Even though the binder may be made up of relatively light stock, it is capable of properly holding and supporting a heavy, thick binding because of the manner in 15 which the panels and strips are continuously connected in edge to edge relation.

The easel supporting strips 35, 36 in the set up relation are firmly held at the top by the side panels 25, 26 and firmly held at the bottom by the positioning or 20 spacing strips 41, 42, which are secured to the front and back covers 20, 21, FIGS. 8 and 13.

This arrangement also provides for the flat folding relation shown in FIG. 5. The slanted height of the easel board is determined by the width of strips 35, 36 25 and the width of the positioning strips 41, 42 is determined by the extent the support strips 35, 36 extend beyond the covers 20, 21.

This inclined height can be changed by varying width of strips 35, 36 and in doing so the width of the positioning strips 41, 42 will be changed accordingly.

In reducing width of strips 35, 36, the width of the positioning strips will be increased proportionately so as to preserve the relations shown in FIGS. 5 and 8 for maintaining the flat folding condition on the one hand and 35 the upstanding relation of the supporting strips on the other hand.

In the first form of the invention illustrated the intermediate panel 30 may be considered as part of the binding means, hingedly connected as it is with the inner 40 edges of the side panels and similar in that respect to the flanges 49, 50 carrying the binder posts and hingedly connected with the inner edges of the side panels in the second form of the invention shown.

What is claimed is:

1. A heavy binder and easel construction comprising the combination of

a back and hingedly connected covers foldable into closed back formation and to unfold into open flat formation,

an easel board overlying said back and covers in the said open, flat relation,

said easel board consisting of flat side panels overly-

45
50

ing said covers at opposite sides of the back and hingedly connected along their lower edges with the lower edges of said covers enabling said panels to be hinged upwardly at their upper edges into inclined position overstanding said covers,

sheet binding means between said side panels, overstanding said back and hingedly connected along opposite side edges with the inner edges of said side panels in line with the hinging connections of the covers with the back,

supporting strips for supporting the upper ends of said side panels coextensive with said side panels and having their lower edges hingedly connected with the upper edges of said side panels, enabling said supporting strips to fold back and hinge downwardly into supported engagement with the covers beneath the same,

positioning strips at the upper ends of and coextensive with said covers and hingedly connected at their lower edges with the upper edges of said covers enabling said positioning strips to fold upwardly and down over the top of said covers, and

hinge connections between the upper edges of said supporting strips and the upper edges of said positioning strips for causing said positioning strips to follow and be located by said positioning strips when the latter are hinged downward into the supporting position and whereby said positioning strips will then locate and hold the supporting strips in substantially upright position supporting the easel board in inclined easel forming relation described.

2. The invention according to claim 1 in which said sheet binding means includes

a back panel overlying and of approximately the size of the said back, hingedly connected along its side edges with the inner edges of said side panels in line with the cover-to-back hinges and hingedly connected at the lower end with the lower end of the back, and

narrow supporting and positioning strips hingedly connected with said back panel and said back and hingedly connected together and located between and hingedly connected with said first mentioned supporting and positioning strips to operate in conjunction with said first mentioned supporting and positioning strips.
